UNITED STATES PATENT OFFICE.

PETER PANIPENTO CATALANO, OF DUNKIRK, NEW YORK.

AUTOMATIC GAS-LIGHTER AND SAFETY CUT-OFF DEVICE.

1,347,532.

Specification of Letters Patent. Patented July 27, 1920.

Application filed August 14, 1919. Serial No. 317,577.

To all whom it may concern:

Be it known that I, PETER P. CATALANO, a citizen of the United States, residing at Dunkirk, in the county of Chautauqua and State of New York, have invented certain new and useful Improvements in Automatic Gas-Lighters and Safety Cut-Off Devices, of which the following is a specification.

This invention relates to combined automatic gas lighters and safety cut-off devices, and has for one of its objects to provide an attachment for a gas burner including a sparker device, electrically controlled, to coöperate with a pilot device, and an automatically operated safety cut-off which becomes operative in event of the gas pressure being reduced to a sufficient extent to extinguish the light.

Another object of the invention is to produce a device including a sparker and an automatic cut-off operative by the same movement which opens the gas supply valve.

With these and other objects in view, the invention consists in certain novel features of construction, as hereinafter shown and described and then specifically pointed out in the claims; and in the drawings illustrative of the preferred embodiment of the invention—

30 Figure 1 is a vertical sectional elevation of the improved device in operative position, or with the gas turned on.

Fig. 2 is a side elevation of the part shown in Fig. 1.

35 Fig. 3 is a perspective view of a portion of the improved apparatus, partly in section, to illustrate the construction and operation of the safety cut-off.

Fig. 4 is a view similar to Fig. 1 illustrating the parts in closed and locked position.

The improved device includes a casing or shell 10 having a burner tip 11 at one end. The intake or gas supply pipe is represented 45 at 12 and is coupled by an elbow 13 and a nipple 14 to the lower end of the shell 10. The elbow 13 is extended upwardly and provided with a valve seat to receive a plug valve 15 with passages 16 in the body of 50 the elbow, the valve 15 constituting the device for controlling the flow of gas from the intake to the burner tip. The shell 10 is reduced toward the nipple engaging portion, and within the reduced portion is located a sleeve 17 closed at one end except 55 for a gas passage 18. The nipple 14 is in

ternally threaded, and located within the nipple is another sleeve 19 closed at the ends except for gas passages 20—21. The passage 20 of the sleeve 19 is provided 60 with a globular closing valve 22 having a stem 23 extending through the passages 20 and 21.

The valve 22 is adapted to be operated wholly by the gas pressure, and when the 65 pressure falls below a predetermined point the ball valve drops and automatically cuts off the flow until the pressure is restored, as hereafter more fully explained.

Located within the reduced portion of the 70 shell 10 is a weight 24 in constant engagement with the valve 22 and operating to force the latter upon its seat. A stem 25 rises from the weight member 24 and extends through the passage 18, and is provided 75 at its upper end with a laterally directed enlargement or head 26. Attached to the stem 25 and spaced from the enlargement 26 is another enlargement 27, and loosely engaging the stem 25 between the 80 enlargements 26—27 is a plate 28, the latter resting by one end upon the shoulder at the juncture of the body portion of the shell 10 and its reduced lower portion. The stem 25 and its enlargements 26—27 are 85 movable vertically through the plate 28. Mounted for rotation through the shell 10 is a shaft 29, and connected to the shaft within the casing is an arm 30 having an offset lower end 31 forked to engage around 90 the stem 25 between the enlargement 26 and the plate 28. Connected to the shaft 29 intermediate its ends externally of the shell 10, is a rod 32 carrying a weight 33 at its longer end. The shorter end of the rod 32 95 terminates in an eye 34 to receive a pull chain 35. By this arrangement the weight 33 operates to rotate the shaft 29 and move the forked end 31 of the arm 30 beneath the enlargement 26 and against the plate 28 100 and holds the latter yieldably in downward position, or resting upon the shoulder of the shell 10. The downward movement of the plate 28 by the action of the arm 30 causes the enlargement 27 to force the 105 weight 24 against the valve 22 and thus locks the latter in closed position.

Connected intermediate its ends to the stem of the plug valve 15 is an arm 36 having a pull chain 37 connected thereto at one 110 end and a pull chain 38 connected thereto at the other end. The pull chain 35 of the

arm 32 is coupled at 39 to the pull chain 37, so that when the chain 37 is actuated the chain 35 will be correspondingly actuated.

Connected at 40 to the elbow 13 is a relatively small pipe 41 turned at its lower end and directed upwardly along side the shell 10 as shown in Fig. 2, and terminates near the gas escaping orifices 42 of the burner tip. The member 41 is provided with a plurality of minute orifices 43, and constitutes the principal member of the pilot burner of the device.

Connected to the member 41, preferably at its bend, is a hanger 44 insulated from the member 41 in any suitable manner. Pivoted at 45 in the hanger 44 is a toothed disk 46. Mounted to swing upon the pivot 45 is a lever arm 47 carrying a spring controlled pawl 48 in engagement with the teeth of the disk 46. A spring 49 is connected to hold the lever 47 yieldably in its upper position. A pull chain 50 is connected at one end to the lever arm 47 and at the other end at 51 to the pull chain as shown in Fig. 2. Extending from the hanger 44 is a pin 52 having a conductor wire 53 engaged with the terminal 54 of the conductor wire extending into the path of the teeth of the disk 46. Leading from the pivot 45 of the hanger 44 is another conductor wire 55, the conductor wires 53-55 being coupled to the poles of a source of electric energy, for instance a battery indicated at 56. The lever member 47 is so arranged that it holds the disk 46 normally with its teeth out of contact with the terminal 54 of the conductor 53, thus maintaining the electric circuit normally broken. The device just described provides a simple and efficient sparking device whereby an electric spark is produced when the lever 47 is moved downwardly through the influence of the pull member 50 to cause the adjacent tooth of the disk 46 to contact with the point 54. The sparker device, it will be noted, is located in close proximity to the pilot member 41 and the orifices 43 thereof.

When the plug valve 15 is closed as in Fig. 4, and the pressure of gas removed from the devices in advance of the plug valve, the weight 24 will descend and close the valve 22 and likewise release the arm 30 and permit the weight 33 to move the arm 30 downward and engage the forked terminal 31 against the plate 28, and thus lock the valve 22 in closed position. When the pull member 37 is operated to open the plug valve 15 the pull member 35 is operated simultaneously therewith and depresses the arm 32 at its shorter end and withdraws the locking member 30-31 from the member 28 and releases the valve 22. The pressure of the gas elevates the valve 22 against the pressure of the weight 24 and simultaneously elevates the stem 25 and causes the enlarge-

ment 27 to elevate the plate 28 against the forked portion 41 of the arm 30 and holds the latter in open position, and this position will be maintained as long as the pressure of the gas continues. At the same time that the pull member 37 is operated to open the plug valve 15 the sparker device is likewise operated by the pull member 50 and the gas escaping through the orifices 43 and within the pilot member 41 are ignited and ignite the gas as it passes through the orifices 42 of the tip. The downward movement of the arm 47 is only for a moment as the spring 49 operates to return the arm to its upward position and again breaks the circuit between the disks 46 and the point 54. If the burner 11 is associated with a "mantle" the flame from the pilot member will ignite the gas which flows through the mantle, or the pilot member may be continued with its outlet adjacent to or above the upper end of the mantle to ignite the latter from above.

The improved device is simple in construction, can be inexpensively manufactured and adapted without material structural change.

It sometimes happens that the pressure of gas in the supply pipes is reduced below the normal, to an extent sufficient to extinguish the flames at the burner tips, and then if the supply valves are not closed the pressure when restored will escape into the room. With the improved device applied to the burner in event of the pressure being thus reduced, the weight operated lever 30 automatically operates to close the valve 22 and locks it in closed position, and effectively prevents the escape of the gas even if the plug valve 15 is left open.

Thus all danger from the escape of the gas in event of an interruption of the flow or the accidental decrease of pressure is obviated.

When the pressure of the gas becomes high enough to be detrimental to the mantle attached to the burner, the pressure actuated valve 22 elevates the globular member 24 and causes the same to partly close the opening 18 whereby the supply of gas to the mantle is not permitted to exceed a predetermined pressure.

Having thus described the invention, what is claimed as new is:

1. A valve including a vertical casing having upper and lower vertically aligned valve seats, a pressure actuated valve for the lower valve seat, and a weighted valve arranged directly beneath said upper valve seat and adapted to engage the same as the pressure within the casing increases, said weighted valve being adapted to engage said pressure actuated valve for seating the same as the pressure decreases.

2. A valve including a vertical casing hav-

ing upper and lower vertically alined valve seats, a pressure actuated globular valve for the lower seat, a weighted globular valve arranged directly beneath said upper valve 5 seat and adapted to engage the same as the pressure within the casing increases, said weighted globular valve being in contact with the globular valve of the lower seat, a manually operable valve for the casing, and 10 means for locking the first named globular valve in a seated position when the pressure within the casing is decreased.

3. In a device of the class described, a body provided with a controlling valve and 15 with an intake at one end and a burner at the other end, said body having an intermediate valve seat between the controlling valve and the burner, a valve adapted to be seated on the intermediate valve seat, a 20 weight bearing upon said intermediate valve, a stem extending from said weight and having lateral enlargements in spaced relation, a plate movable on said stem between said enlargements, a shaft extending through said body, an arm carried by said shaft and having 25 an offset adapted when the shaft is in one position to engage between the plate

and one of the enlargements and to be engaged by the plate and held in withdrawn position when the shaft is in another position, and means whereby the operation of opening the controlling valve likewise operates the shaft and the arm connected therewith. 30

4. In a device of the class described, the 35 combination with a burner having a burner tip at one end, a manually operable valve for the burner, an elongated pilot burner extending from said first named burner and terminating adjacent said tip, a hanger secured to said pilot burner, a ratchet wheel rotatably carried by said hanger, a sparking device arranged adjacent the teeth of said ratchet wheel and adapted to be engaged by the same, a source of electrical energy 40 45 connected with said ratchet wheel and said sparking device, a lever actuated pawl adapted for engaging said ratchet wheel, and means connected to said manually operable valve and the lever of said pawl whereby the 50 valve and the lever may be operated together.

In testimony whereof I affix my signature.

PETER PANIPENTO CATALANO. [L. s]
